United States Patent Office.

WALTER FITZGERALD, OF BOSTON, MASSACHUSETTS.

Letters Patent No. 99,423, dated February 1, 1870.

IMPROVEMENT IN VALVES OF ROTARY ENGINES.

The Schedule referred to in these Letters Patent and making part of the same

To all whom it may concern:

Be it known that I, WALTER FITZGERALD, of Boston, in the county of Suffolk, and State of Massachusetts, have invented certain Improvements in Rotary Engines, of which the following is a full, clear, and exact description, reference being had to the accompanying drawings, making part of this specification, in which—

Figure 1 is a perspective view of my improved rotary engine.

Figure 2 is a transverse section through the same.

Figure 3 is a longitudinal section, on the line $z z$ of fig. 2.

Figure 4 is a perspective view of the pistons, detached from the cylinder.

Figure 5 is a perspective view of the valve.

My invention has for its object to provide a rotary engine, in which the steam can be worked expansively, and consists in the employment of a revolving valve of peculiar construction, in combination with a piston, provided with a slide working within a cylinder, whereby the desired end is effected, and the steam economized to a greater degree than heretofore in this class of engines.

To enable others skilled in the art to understand and use my invention, I will proceed to describe the manner in which I have carried it out.

In the said drawings—

A represents the bed-plate, upon which rests the casing or cylinder B , which is divided centrally by a partition, a , into two compartments, $C D$, which are closed by heads $E G$, secured by bolts to the ends of the cylinder.

H is the main shaft, extending through the heads $E G$, and passing through the interior of the cylinder to one side of its centre.

Upon this shaft, and concentric therewith, are secured two pistons, $I K$, the diameter of each of which is less than that of the interior of the cylinder B , with which they come in contact at a point midway between the induction and exhaust-ports, a steam-tight joint being insured by means of a spring-packing, 7 , fitted into a groove in the interior of the cylinder.

Each piston $I K$ is provided with a sliding abutment, $I' K'$, composed of a solid portion, b , which fits into a groove, c , extending longitudinally through the piston, and is held in place by two side pieces, $d e$, which slide in grooves in the ends of the piston, each side piece being provided with a slot, 8 , through which the main shaft projects, by which construction the abutment is allowed to move as required.

The length of each of the side pieces $d e$ is such, that as the piston revolves, the portion b , which is provided with a spring-packing, g , will be kept con-

tinually in contact with the interior of the cylinder by the contact of the ends of the side pieces $d e$ with the opposite side of the cylinder, thus insuring the portion b of the abutment being in a proper position to be acted upon by the steam, as required; and by thus constructing the sliding abutment, so that the contact of one end with the interior of the cylinder will guide and force out the other end, I am enabled to dispense with the springs heretofore used for this purpose, which are objectionable, on account of their liability to get out of order.

Instead of the abutments $I' K'$ being placed in the same relative position, with respect to the induction and exhaust-ports, they are set with a variation of one hundred and eighty (180) degrees, so that the full force of the steam will act upon one at the time when it has ceased to act upon the other. The engine thus becomes double-acting, producing an effect similar to that caused by placing two cranks at different angles upon a single shaft.

$h i$ are the induction-ports, and $k l$ the exhaust-ports, the former $h i$ communicating with a circular opening, m , which extends longitudinally through an enlargement, n , on the cylinder B .

Within this opening m , is fitted the valve L , consisting of a circular rod, provided with notches $o p$, through which the steam is admitted to the induction-ports, when the valve L is rotated into the proper position, by means of a gear, M , at one end, which engages with a gear, N , on the main shaft H .

The position of the notches $o p$ is such, and the valve is so set, that steam will be admitted the moment the abutment of each piston has passed its exhaust-port h or i . The steam then commences to act upon the abutment, and rotate the piston, the revolution of the valve causing the induction-port to be wide open when the abutment reaches the point 9 , and entirely closed when it reaches the point 10 . The steam being then entirely cut off, will work expansively, and exert a pressure upon the abutment until it reaches the exhaust-port; after passing which, the steam will commence to be discharged, and the operation will continue as before, the steam acting with full force upon the abutment of one piston, while that of the other is passing from the exhaust-port to the induction-port.

It is evident, that instead of two pistons, each working in a separate compartment, as described, a single-acting engine, having one piston only, could be employed; but in such case, a heavy fly or balance-wheel would be required, to prevent any liability of the engine stopping while the abutment is passing from the exhaust to the induction-port.

By the employment of a rotating valve, constructed

as above described, I am enabled to cut off the steam, and work it expansively.

Claim.

What I claim as my invention, and desire to secure by Letters Patent, is—
The rotating valve L, with its notches o p, in com-

bination with the cylinder B, and one or more revolving pistons, constructed and operating substantially in the manner and for the purpose set forth.

WALTER FITZGERALD.
